CIRCUIT BREAKER

David C. Prince, Swarthmore, Pa., assignor to
General Electric Company, a corporation of
New York

Application February 18, 1935, Serial No. 7,085

25 Claims. (Cl. 200—116)

My invention relates to circuit breakers of the type which is manually operable between on and off positions and in response to overload current is automatically operable to an open circuit position, and has for an object the provision of a reliable, inexpensive and compact circuit breaker.

More particularly, my invention has for its object a spring snap acting operating mechanism for circuit breakers wherein the operating force required to operate manually the circuit breaker between open and closed positions is greatly decreased, while the biasing force on the movable contact remains at a high value.

Further objects of my invention are the provision of means associated with the manually operated mechanism for rigidly engaging the movable contact to initiate positively its movement at substantially the same time that the spring snap acting mechanism is rendered effective, and means for returning the handle to a mid-position upon overload opening of the breaker.

My invention has particular application to circuit breakers provided with overcenter spring snapping mechanism wherein a pivotally mounted operating handle is provided for moving one end of the overcenter spring from one side to the other of a dead center position to effect snap movement of the movable contact. It is advantageous in a device of this character to provide a pivoted handle which is relatively short in order that its arc of movement between the on and off positions may be relatively great. It will be understood that one end of the overcenter spring is ordinarily attached to the pivoted operating member at some point spaced from its pivot. This arrangement has the disadvantage that due to the substantial angle between the handle and the spring, the spring applies a force of very considerable magnitude in opposition to movement of the handle.

In carrying out my invention I greatly reduce the force applied by the spring to the handle by providing an intermediate relatively long pivoted link or arm extending lengthwise of the spring and to the movable end of which the movable end of the spring is attached. This arrangement provides for the required range of movement of the end of the spring with but little angular displacement between the spring and the link and, consequently, the spring offers but little opposition to movement of the link. I also provide an operating connection between the handle and the relatively long link whereby I obtain the

advantages of a relatively short operating handle and lower required operating force.

I also provide a positive operating connection between the intermediate link and the movable contact whereby the contact is forcibly moved at substantially the same time that the overcenter spring becomes effective to continue the movement of the contact. This feature is of particular advantage in opening the breaker since the initial positive movement of the contact assures separation of the contacts for snap action by the spring even though they may be welded together from any cause, such as arcing.

I furthermore pivotally mount the fixed end of the intermediate link at a point within the range of movement of the movable contact. By means of this arrangement I provide for a reversal of the bias of the overcenter spring on the link upon movement of the switch to the open position in response to overload conditions so that the link, and through it the handle, is finally biased to the off position and is brought to rest in a mid-position. This mid-position of the handle furnishes an indication of the overload opening of the circuit breaker.

For a more complete understanding of my invention, reference should now be had to the drawing wherein I have shown in Fig. 1 an elevation, partly in section, of a circuit breaker embodying my invention; Fig. 2 illustrates the circuit breaker of Fig. 1 but with the parts in the positions assumed at the instant the link rigidly engages the movable contact; Fig. 3 illustrates the circuit breaker of Fig. 1 after it has been tripped in response to an overload and before the handle returns to the mid-position; Fig. 4 illustrates the circuit breaker of Fig. 1 after the handle has been automatically moved to the mid-position; and Fig. 5 is a fractional elevation taken on the line 5—5 of Fig. 1.

Referring to the drawing, I have shown my invention in one form as applied to a circuit breaker 10 of the type described and claimed in a co-pending application of Ludwig S. Walle, Serial No. 667,856, filed April 25, 1933, entitled "Circuit breaker", and assigned to the same assignee as the present invention. The invention of said Walle application was made prior to my invention and I do not herein claim anything shown or described in said Walle application which is to be regarded as prior art with respect to this present application.

Referring to Figs. 1 and 4, the circuit breaker 10 is provided with a base 11 and a cover 12, both formed of insulating material. The operating

25

30

35

40

45

50

55

mechanism for operating a slidably movable contact 13 between open and closed circuit positions with reference to a stationary contact 14 is mounted upon a U-shaped metallic frame 15 suitably secured to the base 11 as by screws (not shown). An operating member or handle 16 is carried by a support 17 formed of sheet metal which is mounted on a pivot pin 18 carried by the frame. The handle 16 is operable between 10 on and off positions to effectuate a snap action of the movable contact 13 by means of a pair of overcenter springs 19 and 20 which are normally under a predetermined tension. The effort required to operate the handle 16 is minimized by 15 supporting corresponding ends of the overcenter springs on the respective ends of a pin 21 extending through a longitudinal slot 22 provided in the handle and supported on corresponding ends of a pair of relatively long links 23 and 24 20 which are pivoted respectively at their opposite ends on a pivot pin 25 supported by the frame 15. The opposite ends of the overcenter springs 19 and 20 are secured to the respective ends of a pin 26 extending through slots 27 provided in the 25 frame and through a slot (not shown) provided in the movable contact, the pin 26 being carried by the spaced free end of a guide link 28 which end straddles one end of the movable contact 13. This guide link, pivoted at its opposite end on the 30 pivot pin 18, is shown as consisting of two parallel links or portions joined into a unitary member by a cross connecting portion 29 which cooperates with an overload tripping member 30. This member 30, pivoted at 18, is normally restrained 35 against movement by an overload tripping spring 31 by means of a bimetallic thermal element 32 formed of dissimilar metals and which is connected in circuit with the movable contact 13 by means of a flexible shunt or conductor 33.

40 In order to operate the circuit breaker to the open circuit position, the handle 16 is moved from the on to the off position. The resulting movement of the overcenter springs 19 and 20 past the dead-center position determined by the 45 pivot pin 18 reverses the bias applied to the movable contact 13 and causes it to operate with a snap action to the open circuit position.

If the pin 21 and the overcenter springs 19 and 20 were supported by the relatively short handle 50 16, the full force of the springs would apply a torque to the handle the magnitude of which would depend on the angular displacement between the handle and the spring, i. e. the shortest distance between the line of action of the 55 springs and the center of the pivot pin 18. With the required movement of the relatively short handle between on and off positions, the pin moves through a relatively wide angle with a correspondingly large angular displacement between 60 the handle and the spring. With this arrangement the required handle operating force due to the initial wide angular displacement and the relatively great increased elongation of the 65 springs upon movement of the handle was so great as to be quite objectionable, particularly when a plurality of mechanisms were simultaneously operated by a single handle.

In accordance with my invention, however, the links 23 and 24 by supporting the pin 21 and 70 the ends of the overcenter springs greatly reduce the spring force applied to the handle 16. Inasmuch as the rigid links 23 and 24 are substantially in line with the overcenter springs 19 and 20, the only biasing force applied to the handle 75 is the component of force which tends to rotate

the links 23 and 24. The resulting torque will vary with the angle between the springs and the links, i. e. with the distance that the axis of the pin 25 is separated from the line of action of the overcenter springs 19 and 20. Preferably, the distance is relatively small with the handle either in the on or the off position. Since a relatively small torque is applied to the handle 16 by the springs, it follows that only a relatively small torque is necessary to move the handle 16 10 between the on and off positions.

The slot 22 in the handle support 17 extends along a radial line of the handle and forms in conjunction with the pin 21 a lost motion driving connection with the links 23 and 24. Upon rotation of the handle 16 the pin 21 and the ends of the overcenter springs 19 and 20 rotate in a relatively flat arc which is determined by the length of the links 23 and 24. Consequently, the overcenter springs are not materially elongated 20 as the handle is moved towards its mid-position corresponding to the dead-center position of the springs, and as a result the spring tension, and force applied by the spring to the handle, are not appreciably increased. The force applied by 25 the springs to the movable contact 13, however, remains at its initial high value and assures a high contact pressure and rapid snap action movement between open and closed circuit positions. The total reduction in the operating force 30 over a similar structure where the springs are carried by the handle has been found to amount in a typical device to approximately 65 per cent. This decreased operating force becomes of even greater importance in connection with multipole circuit breakers provided with a plurality of 35 operating mechanisms. Such multipole circuit breakers when constructed in accordance with the present invention can be operated with substantially the same effort that is required to 40 operate a single pole circuit breaker of the old type.

Under some conditions of operation the movable contact 13 may have a tendency to become welded to the stationary contact 14 due to arcing 45 between the contacts. In order to insure the positive opening of the contacts under such abnormal conditions, I provide slots in the respective links 23 and 24, only one slot, i. e. 34, in the link 23 being shown. The slot in the link 50 24, however, is identical with the slot 34. The relation between the pivot pin 25, the slots, and the over-center springs 19 and 20 is such that the walls of the slots in the links 23 and 24 rigidly engage the pin 26 at substantially the same 55 instant that the over-center springs are moved past the dead-center position determined by the axis of the fixed pivot pin 18. This relationship of the parts is shown in Fig. 2. A slight additional movement of the handle 16 towards the 60 off position causes the links 23 and 24 to move the contact 13 forcibly away from the stationary contact 14. At the same instant the over-center springs 19 and 20 accelerate the movable contact 13 to the open circuit position. This position is determined by the engagement of the 65 pin 26 with the sides of the slots 27 provided in the U-shaped frame 15, the movable contact 13 having a range of movement between its open and closed circuit positions.

Besides positively initiating movement of the contact 13 from the closed towards the open position, the links 23 and 24 serve to initiate movement of the contact 13 toward the closed circuit position, the pin 26 as shown in Fig. 4 then en- 70 75

gaging the links at the opposite ends of the slots. The result is a higher closing speed for the movable contact inasmuch as the over-center springs 19 and 20 accelerate the movement of the contact 13 more than they would if the acceleration of the contact were initiated from standstill. As the handle 16 is moved from the off to the on position, the movable contact 13 is first moved by the links 23 and 24 and as the over-center springs 19 and 20 are moved past their dead-center position the movable contact 13 is accelerated to the closed circuit position. In order to obtain uniformity in operation in the two directions the fixed axis of the links, i. e. the axis 15 of pivot pin 25, is located substantially midway of the range of movement of the movable contact 13.

It should here be noted that the relatively long links 23 and 24 with their respective slots located fairly close to their fixed axis or pivot pin 25 provide a substantial mechanical advantage to multiply the force of the handle as applied to the movable contact 13. An additional mechanical advantage is secured, which also minimizes 25 the effort required to operate the handle 16 between on and off positions, by reason of the difference in the length of lever arms of the handle 16 on pin 18 and the pin 21 on the pin 18. Consequently, the outer end of the handle 30 16 when rotated through a given angle moves a greater distance than the pin 21 and the free ends of the links 23 and 24.

In case of an overload, the heat produced in the bimetallic thermal element 32 by the current 35 causes sufficient flexure of the thermal element to release the overload tripping member 30. Preferably, the thermal element is U shaped and has its two ends secured respectively to terminal lugs 35 and 36, whereby it is supported, its middle 40 or base portion 37 normally engaging and holding the tripping member 30. As soon as it is released, Fig. 3, the overload tripping spring 31 rotates the tripping member 30 in a clockwise direction, as viewed in the drawing, until a projecting end 38 of the tripping member rigidly engages the cross portion 29 of the guide link 28 and rotates the guide link 28 in a direction to move quickly the contact 13 to the open circuit 45 position against the bias of the over-center springs 19 and 20.

After the overload opening of the circuit breaker has been initiated, the pin 26 secured to the movable contact is operated across a line taken between the pivot pins 21 and 25. With the circuit breaker in the closed circuit position, the pin 26 is located on one side of the line taken through the centers of the pivot pins 21 and 25 so that the over-center springs 19 and 20 bias 55 the links 23 and 24 in a clockwise direction, the extent of clockwise rotation being limited by the engagement of the links with the base 10, as indicated at 39. However, as soon as the pin 26 is moved to the opposite side of the line taken through the pins 21 and 25, the bias of the over-center springs 19 and 20 is applied to the links 23 and 24 in a direction to rotate them in a counter-clockwise direction. The result is that the links 23 and 24 operate the handle 16 from the on position towards the off position as soon 65 as the pin 26 crosses the line determined by the pins 21 and 25. In this manner the over-center springs perform a double function. The movement of the ends of the springs 19 and 20 attached to the pin 21 from one side to the other 70 of the dead-center position or pivot 18 operates

the movable contact 13 with a snap action. Similarly, movement of the opposite ends of the springs 19 and 20 past a dead-center position determined by the fixed axis of the pivot pin 25 reverses the bias on the links 23 and 24 which 5 reversed bias operates the links and the handle from an on towards the off position.

By utilizing the two dead centers determined by the fixed axes of the pins 18 and 25, the handle 16 can be returned to the off position by 10 a relatively small movement of the pin 26. The movement required may be decreased by locating the pivot 25 nearer to the line taken through the centers of the pins 21 and 26 when in the positions shown in Fig. 1. 15

As the handle 16 is moved by the over-center springs 19 and 20 from the on towards the off position, the tripping member 30 approaches the handle 16. The arrangement is such that the handle 16 and the tripping member 30 come into 20 engagement at substantially the instant that the handle 16 arrives in a position intermediate its on and off positions and the movable contact 13 reaches its open circuit position, as shown in Fig. 4. The intermediate or mid-position of the handle 25 affords a very convenient and satisfactory means of indicating the overload operation of the circuit breaker.

In order to reclose the circuit breaker, the operating handle is rotated in a counter-clockwise 30 direction to the off position, the portion 40 of the handle engaging the tripping member 30 to return it to the restrained position. During this movement energy is stored in the tripping spring 31. If the bimetallic element 32 has not cooled sufficiently to relatch the tripping member 30, the tripping spring 31, upon release of the handle 16, will return the tripping member 30 and the handle to the mid-position and thereby prevent the closure of the circuit breaker. However, as soon 40 as the tripping member 30 is relatched by the bimetallic thermal element 32, it is necessary only to operate the handle 16 from the off position to the on position to close the circuit breaker. It will be observed that the circuit breaker is trip-free, that is to say, the movable contact 13 can 45 not be maintained in engagement with the stationary contact 14 when an overload occurs because the tripping member 30 when released by the thermal element 32 is operated by the tripping spring 31 to open the circuit breaker irrespective of the position of the handle 16 or the bias of the over-center springs 19 and 20. 50

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention. 60

What I claim as new and desire to secure by Letters Patent of the United States is:

1. A circuit breaker comprising a switch member movable between open and closed circuit positions, an operating handle provided with a relatively short radius for movement about a fixed axis between on and off positions, an over-center spring operatively connected at one end to said switch member, and means including a driving connection between said handle and the opposite end of said over-center spring for moving said opposite end of said over-center spring through an arc the radius of which is substantially greater than said radius of said operating handle. 70

2. An operating mechanism comprising a mem- 75

ber having a predetermined range of movement between predetermined positions, a link having a fixed end pivotally mounted within said range of movement and a free end movable between 5 predetermined positions, an over-center spring having one end operatively connected to said member and the opposite end connected to said free end for operating said member with a snap action when said free end of said link is moved 10 from one to the other of its predetermined positions, and means for moving said member independently of said link, the range of movement of said member, the predetermined positions of said link, and the fixed end of said link being so related 15 that movement of said one end of said over-center spring with respect to said fixed end of said link when said member is moved from one to another of its predetermined positions independently of said link is effective to reverse the 20 bias applied by said spring to said link.

3. A circuit breaker comprising a switch member movable between open and closed circuit positions, an over-center spring having one end operatively connected to said switch member, an 25 operating member operable between on and off positions for moving the opposite end of said spring to operate said switch member, supporting means for said opposite end of said spring for maintaining said spring under a predetermined 30 stress, a driving connection between said supporting means and said operating member, and means including said driving connection for minimizing the application of the force of said spring on said operating member.

35 4. A circuit breaker comprising a switch member having a range of movement between open and closed circuit positions, an over-center spring operatively connected at one end to said switch member, a link pivotally supported at one 40 end within the range of movement of said switch member, an operating handle operable between on and off positions, a guide member pivoted at one end and connected at its opposite end to said switch member, and connecting means forming 45 a driving connection between said handle and the opposite ends of said link and said over-center spring.

5. A circuit breaker comprising a switch member having a range of movement between open 50 and closed circuit positions, an operating member having a range of movement between on and off positions, a link having a fixed end pivotally mounted within said range of movement of said switch member, the opposite free end of said link 55 being operatively connected to said operating member, an over-center spring one end of which is operatively connected to said switch member and the opposite end of which is operatively connected to said free end of said link, said operating member when moved between said on and off positions operating said spring to move with a snap action said movable contact between said 60 open and closed circuit positions.

6. A circuit breaker comprising a switch member having a range of movement between open 65 and closed circuit positions, an operating member having a range of movement between on and off positions, a link having a fixed end pivotally mounted within said range of movement of said 70 switch member, the opposite free end of said link being operatively connected to said operating member, an over-center spring one end of which is operatively connected to said switch member and the opposite end of which is operatively connected to said free end of said link, said operat-

ing member when moved between said on and off positions operating said spring to move with a snap action said movable contact between said open and closed circuit positions, and means for operating said movable contact from closed circuit position towards said open circuit position and beyond said fixed end of said link to reverse the bias of said over-center spring on said link to operate thereby said operating member from said on position towards said off position.

7. A circuit breaker comprising contacts one of which is movable relative to the other between open and closed circuit positions, an operating handle, pivot means for mounting said handle for movement between on and off positions, said handle being provided with a slot extending substantially parallel to the radius of the handle, a relatively long link pivoted at one end, its opposite free end being operatively connected to said slot, and an over-center spring one end of which is connected to said free end of said link and the opposite end of which is connected to said movable contact.

8. A circuit breaker comprising a switch member having a range of movement between open 25 and closed circuit positions, an operating member having a range of movement between on and off positions, a link having a fixed end pivotally mounted within said range of movement of said switch member and the opposite free end of said 30 link being operatively connected to said operating member, an over-center spring one end of which is operatively connected to said switch member and the opposite end of which is operatively connected to said free end of said link, said 35 operating member when moved between said on and off positions operating said spring to move with a snap action said movable contact between said open and closed circuit positions, means for operating said movable contact from closed circuit position towards said open circuit position and beyond said fixed end of said link to reverse the bias of said over-center spring on said link to operate thereby said operating member from said on position towards said off position, 40 and means for stopping said operating member between said on and off positions.

9. A circuit breaker comprising contacts, one of which is movable relative to the other between open and closed circuit positions, an operating 50 handle, means pivoting said handle for movement between on and off positions, said handle being provided with a radial slot, a link pivoted adjacent said movable contact, connecting means forming a driving connection between the sides of 55 said slot and said link, an over-center spring one end of which is operatively connected to said movable contact and the other end of which is supported by said connecting means so that when said handle is moved between on and off positions said end of said over-center spring connected to said connecting means moves through an arc determined by the length of said link.

10. A circuit breaker comprising contacts, one of which is movable relative to the other between 65 open and closed circuit positions, an operating member therefor, pivot means mounting said member for movement between on and off positions, said member being provided with a radial slot, a link, connecting means carried by one end 70 of said link and forming a driving connection with the walls of said slot, pivot means mounting the opposite end of said link adjacent the said movable contact, an over-center spring the ends of which are connected respectively to said connect- 75

ing means and to said movable contact, the relation of said pivot means for said member and said link being such that said over-center spring biases said movable contact in said closed circuit position and said member in said on position, means for operating said movable contact and one end of said spring towards said open circuit position to reverse the bias which said over-center spring applies to said link whereby said operating member is moved towards said off position, and means for bringing said operating member to a standstill in a position intermediate said on and off positions.

11. A circuit breaker comprising contacts, one of which is movable relative to the other between open and closed circuit positions, an operating member therefor, pivot means mounting said member for movement between on and off positions, said member being provided with a radial slot, a link, connecting means carried by one end of said link and forming a driving connection with the walls of said slot, pivot means mounting the opposite end of said link adjacent to said movable contact, an overcenter spring connected between said connecting means and said movable contact, the relation of said pivot means for said member and said link being such that said overcenter spring biases said movable contact in said closed circuit position and said handle in said on position, and means for operating said movable contact towards said open circuit position and to a position to reverse the bias applied by said overcenter spring to said link whereby said link is rotated in a direction to move said operating member towards said off position.

12. A circuit breaker comprising a switch member having a range of movement between open and closed circuit positions, an over-center spring connected at one end to said switch member, a link one end of which is pivoted for rotation about a fixed axis located within the range of movement of said switch member, an operating handle movable about a fixed axis between on and off positions, a guide member one end of which is movable about a fixed axis and the opposite end of which is connected to said switch member, and connecting means forming a driving connection between said handle and the opposite ends of said link and said over-center spring.

13. A circuit breaker comprising a switch member having a range of movement between open and closed circuit positions, an over-center spring operatively connected at one end to said switch member, a link having one end rotatable about a fixed axis located within the range of movement of said switch member, an operating handle operable about a fixed axis between on and off positions, said fixed axis being located on one side of said range of movement and said fixed axis for said link being located on the opposite side of said range of movement, a guide member having one end pivoted about a fixed axis and its opposite end connected to said switch member, and connecting means forming a driving connection between said handle and the opposite ends of said link and said over-center spring, said handle being provided with a slot forming a lost motion connection to provide for relative movement of said connecting means with reference to said handle.

14. A circuit breaker comprising a switch member having a range of movement between open and closed circuit positions, an over-center spring connected at one end to said switch member, a

link of greater length than said over-center spring, one end of said link being mounted for rotation about a fixed axis, an operating handle mounted for rotation about a fixed axis between on and off positions, a guide member pivoted at one end about a fixed axis and connected at its opposite end to said switch member, and connecting means forming a driving connection between said handle and the opposite ends of said link and said over-center spring, said handle being provided with a slot to provide for movement of said connecting means to minimize thereby the effort required to move said handle between said on and off positions.

15. A circuit breaker comprising a switch member having a range of movement between open and closed circuit positions, an over-center spring connected at one end to said switch member, an operating handle movable about a fixed axis between on and off positions, a link pivotally supported about a fixed axis remotely located from said axis for said handle, connecting means for supporting the opposite ends of said over-center spring and forming a driving connection with said handle, said connection including a slot whereby the elongation of said spring when said handle is moved between on and off positions is determined by the length of said link.

16. A circuit breaker comprising a switch member having a range of movement between open and closed circuit positions, an operating handle pivoted for movement between on and off positions, said handle being movable about a relatively small radius, a link pivotally supported at one end within the range of movement of said switch member the opposite free end of said link being movable through a relatively flat arc, connecting means forming a driving connection between said free end of said link and said operating handle, said connecting means including a slot to provide relative movement between said connecting means and said handle, an over-center spring connected at one end to said switch member and at its opposite end to said connecting means so that when said handle is moved between said on and off positions said over-center spring is moved from one side to the other of a dead-center position to operate said switch member with a snap action the lengthening of said spring during said movement of said handle being determined solely by the radius of said link.

17. A circuit breaker comprising a switch member having a range of movement between open and closed circuit positions, an operating member having a range of movement between on and off positions, a link having one end mounted above a fixed axis within said range of movement of said switch member and the opposite free end of said link being operatively connected to said operating member, an over-center spring having one end operatively connected to said switch member and the opposite end operatively connected to said free end of said link, said operating member when movable between said on and off positions operating said spring to move with a snap action said movable contact between said open and closed circuit positions, and means for causing operation of said movable contact from said closed position towards said open position and beyond said fixed end of said link to reverse the bias of said over-center spring on said link, said link thereupon operating said operating member from said on position towards said off position.

18. A circuit breaker comprising a switch mem-

ber having a range of movement between open and closed circuit positions, an operating member having a range of movement between on and off positions, a link having one end mounted on a fixed axis within said range of movement of said switch member and the opposite free end operatively connected to said operating member, an over-center spring having one end connected to said switch member and the opposite end operatively connected to said free end of said link, said operating member when moved between said on and off positions operating said spring to move with a snap action said switch member between said open and closed circuit positions, means for causing operation of said switch member from said closed position towards said open position and beyond said fixed end of said link to reverse the bias of said over-center spring on said link, said link thereupon operating said operating member from said on position towards said off position, and means for bringing said operating member to a standstill midway of said on and off positions.

19. A circuit breaker comprising a switch member having a range of movement between open and closed circuit positions, an over-center spring connected at one end to said switch member, an operating handle operable between on and off positions for moving the opposite end of said over-center spring to operate said switch member between said open and said closed circuit positions with a snap action, a link pivotally supported at one end within the range of movement of said switch member, means forming a driving connection between the opposite end of said link and said operating handle, said link being provided with means intermediate its ends for engaging said switch member to initiate movement of said switch member towards one or the other of its positions at substantially the instant said over-center spring initiates said snap action movement of said switch member.

20. A circuit breaker comprising a frame, a switch member having a range of movement between open and closed circuit positions, an operating handle pivotally supported to said frame on one side of said range of movement for operation between on and off positions, an over-center spring connected at one end to said switch member for operating said member with a snap action between said open and closed circuit positions, a link having one end pivotally mounted on said frame on the opposite side of said range of movement of said switch member, said handle being provided with a radial slot, connecting means forming a driving connection with the sides of said slot and supporting said opposite ends of said link and the opposite end of said over-center spring, said link being provided with means for rigidly engaging said switch member to initiate movement of said switch member at substantially the same instant said over-center spring applies its bias to said switch member to operate it with a snap action from one to the other of its positions.

21. A circuit breaker comprising a frame, a switch member having a range of movement between open and closed circuit positions, an operating handle pivotally supported to said frame on one side of said range of movement for operation between on and off positions, an over-center spring connected at one end to said switch member for operating said member with a snap action between said open and closed circuit positions, a link having one end pivotally mounted on

said frame on the opposite side of said range of movement of said switch member, said handle being provided with a radial slot, connecting means forming a driving connection with the sides of said slot and supporting said opposite ends of said link and the opposite end of said over-center spring, said link being provided with means for rigidly engaging said switch member to initiate movement of said switch member at substantially the same instant said over-center spring applies its bias to said switch member to operate it with a snap action from one to the other of its positions, and means for operating said movable contact from said closed circuit position towards said open circuit position and beyond said fixed end of said link to reverse the bias of said over-center spring on said link, said link thereupon operating said operating member towards said off position, and means for stopping said operating member midway of said on and off positions.

22. A circuit breaker comprising a frame, a switch member having a range of movement between open and closed circuit positions, an operating handle pivotally supported on said frame on one side of said range of movement for operation between on and off positions, an over-center spring connected at one end to said switch member for operating said member with a snap action between said open and closed circuit positions, a link having one end pivotally mounted on said frame on the opposite side of said range of movement of said switch member, said handle being provided with a radial slot, connecting means forming a driving connection with the sides of said slot and supporting the opposite ends of said link and the opposite end of said over-center spring, said link being provided with means for rigidly engaging said switch member to initiate movement of said switch member at substantially the same instant said over-center spring applies its bias to said switch member to operate it with a snap action from one to the other of its positions, a guide member pivoted at one end and connected at its opposite end to said switch member, a tripping member normally biased for movement into engagement with said guide member for operating said guide member and said switch member from said closed circuit position to said open circuit position, overload responsive means normally restraining said tripping member in one position and operable upon the occurrence of a predetermined overload to release said tripping member the resulting movement of said movable contact carrying one end of said over-center spring beyond said fixed end of said link to reverse the bias of said over-center spring on said link, said link thereupon moving said operating member from its on position towards its off position, said tripping member forming a stop for said operating handle to maintain it in a position between said on and off positions to indicate the over-load opening of said circuit breaker.

23. A circuit breaker comprising a switch member having a range of movement between open and closed circuit positions, an over-center spring operatively connected at one end to said switch member, a link one end of which is pivoted for rotation about a fixed axis located within and at one side of the range of movement of said switch member, the opposite free end of said link extending across said range of movement and

being operable between on and off positions, the opposite end of said over-center spring being supported by said free end of said link, and means operable upon movement of said link between 5 said predetermined positions for rigidly engaging said movable switch member to initiate its movement between said open and closed circuit positions.

24. A circuit breaker comprising a switch member having a range of movement between open and closed circuit positions, an operating handle movable about a fixed axis between on and off positions, said handle being provided with a radial slot, a pair of links secured together at 10 one end by a pin which extends through said slot the opposite ends of said links being mounted for rotation about a fixed axis located within the range of movement of said switch member, a guide member having one end movable about 15 a fixed axis and the opposite end connected to said switch member, and a pair of over-center springs having the corresponding ends thereof supported by said pin and the opposite corresponding ends thereof operatively connected to 20 said switch member for operating said switch member between said open and closed positions with a snap action.

25. A circuit breaker comprising a switch member having a range of movement between open and closed circuit positions, an over-center spring connected at one end to said switch member, a link having one end pivoted for rotation about 5 a fixed axis substantially within and to one side of said range of movement of said switch member, an operating handle movable between on and off positions about a fixed axis located on the opposite side of said range of movement, a 10 guide member having one end movable about a fixed axis and the opposite end connected to said switch member, connecting means forming a lost motion driving connection between said handle and the opposite ends of said link and 15 said over-center spring, and means for rigidly engaging said switch member to initiate its movement between said open and closed circuit positions comprising a slot formed in said link of such dimensions that said slot operatively engages said switch member at substantially the time said over-center spring moves past its dead-center position. 20
